CHARM BRACELET OR SIMILAR ARTICLE

Leonard R. Abrams, Providence, R. I., assignor to Arden Jewelry Mfg. Co., Providence, R. I., a corporation of Rhode Island

Application May 2, 1957, Serial No. 45,972

Term of patent 7 years

(Cl. D45—4)

FIG. 1

Fig. 1 is a front elevational view of a charm bracelet or similar article, showing my new design;

Fig. 2 is a fragmentary rear elevational view; and Fig. 3 is an edge view thereof.

I claim:

The ornamental design for a charm bracelet or similar article, as shown.
